(**) Term: **14 Years**

(57) **CLAIM**

(21) Appl. No.: **29/305,413**

The ornamental design for a case for optical disk and memory cards, as shown and described.

(22) Filed: **Mar. 20, 2008**

DESCRIPTION

(30) **Foreign Application Priority Data**

Nov. 21, 2007 (HK) 0702988

FIG. 1 is a perspective view from front, top and right side of a case for optical disk and memory cards showing my new design;

(51) **LOC (9) Cl.** **06-04**

FIG. 2 is a perspective view in alternative position thereof;

(52) **U.S. Cl.** **D6/634; D6/629**

FIG. 3 is a front view thereof;

(58) **Field of Classification Search** **D6/407,**

D6/626–635; D9/415, 418, 420, 422, 423,

D9/424, 425, 426, 428, 432, 433, 435, 443;

D3/247, 273, 294, 295, 299–301, 303; 206/307,

206/307.1, 308.1, 309, 311, 312, 313, 310,

206/751; 211/40, 41.1, 41.12; D14/478–479;

D20/29

FIG. 4 is a rear view thereof;

FIG. 5 is a left side view thereof;

FIG. 6 is a right side view thereof;

FIG. 7 is a top view thereof; and,

FIG. 8 is a bottom view thereof.

See application file for complete search history.

The broken lines showing the remainder of the case for optical disk and memory cards are for illustrative purposes only and form no part of the claimed design.
